UNITED STATES PATENT OFFICE.

CLAUDE D. FLETCHER, OF INDIANAPOLIS, INDIANA.

SKIRT-SUPPORTER AND WAIST-STAY.

No. 851,805.

Specification of Letters Patent.

Patented April 30, 1907.

Application filed March 5, 1906. Serial No. 304,151.

To all whom it may concern:

Be it known that I, CLAUDE D. FLETCHER, a citizen of the United States, residing at Indianapolis, in the county of Marion and State of Indiana, have invented certain new and useful Improvements in Skirt-Supporters and Waist-Stays, of which the following is a specification.

The object of my invention is to produce a device by means of which a secure connection may be made between a waist and skirt, or between any two separable garments, the construction being such that all that portion of the fastener carried by the waist may be readily attached thereto and removed therefrom.

The accompanying drawings illustrate my invention.

Figure 1 is a perspective view of the device in use; Fig. 2 an elevation thereof full size; Fig. 3 a perspective view thereof; Fig. 4 a similar view of a modified form; and Fig. 5 a perspective view of one end of my attachment illustrating a modified form of eye to be attached to the skirt.

In the drawings, 10 indicates a strip of thin metal or other suitable material which is sufficiently stiff transversely. Formed in the upper edge of the strip 10 near each end is a notch 11 which thus forms at each end of the strip an upwardly extending hook 12 which hooks converge toward each other so that the end of each hook lies vertically above the bottom of the adjacent notch.

The use is as follows: The average waist is provided at the back, at the waist line, with a tape or strip 13 which serves to hold the gathers 14 in place. In order to adapt this tape for use with my invention I attach the tape to the waist along the upper and lower edges only, by a row or rows of stitches 15, as indicated in Fig. 2, leaving the ends of the tape unattached to the waist and thus forming an open-ended pocket into which the strip 10 may be slipped, the hooked ends 12 projecting from each end of the tape and presenting themselves in position to receive an eye 16 or ring 17 properly attached to the waist band of the skirt. In order to make the connection between the skirt and the waist, it is necessary to draw the waist-band of the skirt tightly about the waist of the wearer, so that the eyes will slip over the upper ends of the hooks 12 and then drop to the bottoms of the notches 11, the natural ex-

pansion of the skirt band thereafter holding the parts against accidental displacement. When it is desired to launder the waist it is merely necessary to withdraw the strip 10 and it may then be readily inserted in position on another waist, it being unnecessary to spend any time in sewing or otherwise attaching the strip to the waist.

If it is desired that the eyes or rings attached to the waist band of the skirt lie very flat it may be desirable to form grooves 19 upon opposite faces of the strip adjacent the base or lowermost portion of the notch 11, as shown in Fig. 4, or a specially prepared ring 17 may be provided with an offset portion 20 which will compensate for the thickness of the plate or strip 10.

I claim as my invention:

1. A device of the class described consisting of a strip of metal all parts of which are substantially in the same plane and having formed in one edge near each end transversely-entering diverging notches forming a pair of converging hooks one at each end.

2. A device of the class described consisting of a strip of material provided at each end with a hook, and offsets formed in the body of the strip adjacent the hooks to receive coöoperating eyes and compensate for the thickness of the strip, substantially as described.

3. A device of the class described consisting of a strip of metal having formed in one edge transversely entering notches, and offsets formed in the body of the strip adjacent the notches to receive coöoperating eyes and compensate for the thickness of the strip.

4. A device of the class described consisting of a strip of metal all parts of which are substantially in the same plane and having formed in one edge near each end transversely entering diverging notches forming a pair of converging hooks one at each end, and offsets formed in the body of the strip adjacent the hooks to receive coöperating eyes and compensate for the thickness of the strip.

In witness whereof, I, have hereunto set my hand and seal at Indianapolis, Indiana, this 2nd day of March, A. D. one thousand nine hundred and six.

CLAUDE D. FLETCHER. [L. s.]
